(57) **CLAIM**

The ornamental design for a cord reel, as shown and described.

DESCRIPTION

FIG. 1 is a top perspective view of a cord reel showing our new design.

FIG. 2 is a top view of the cord reel of FIG. 1.

FIG. 3 is a front view of the cord reel of FIG. 1; and,

FIG. 4 is a side view of the cord reel of FIG. 1.

The broken lines in the drawings depict environmental subject matter only and form no part of the claimed design.

1 Claim, 4 Drawing Sheets

FIG. 1

FIG. 2

FIG. 3

FIG. 4
